[57] ABSTRACT

A discharge luminescence element array comprising a pair of parallel insulating plates and a separator entirely sealed between the pair of insulating plates in which a groove-like gas flow path is provided between one of the plates and the separator for evacuating and providing gas from and to discharge spaces defined by the separator and the pair of insulating plates.

DISCHARGE LUMINESCENCE ELEMENT ARRAY HAVING A GAS FLOW PATH

FIELD OF THE INVENTION

The present invention relates to a structure of a discharge luminescence element array and more particularly to a structure of a discharge luminescent element array for minimizing light leakage or optical cross-talk between luminescent elements.

BRIEF DESCRIPTION OF THE DRAWING

FIG. 1 is a perspective view of a conventional switching matrix comprising a discharge luminescent element array and a photoconductive element array.

FIG. 2 is a cross-sectional view of a conventional arrangement for preventing light leakage or optical cross-talk between the luminescent elements of the discharge luminescent element array.

FIGS. 3a and 3b are plan and cross-sectional views, respectively, of a discharge luminescent element array according to the present invention.

FIG. 4 is a diagram for explaining the path of light leakage between the luminescent elements of the discharge luminescent element array of FIGS. 3a and 3b.

DESCRIPTION OF THE PRIOR ART

Referring to FIG. 1, an arrangement is known comprising a discharge luminescent element array 1 and a photoconductive element array 2 in which the photoconductive element array 2 acts as a switch and the discharge luminescent element array 1 acts as a driver therefor. The discharge luminescent element array 1 consists of an insulator plate 11 having thereon transparent or semi-transparent electrodes 10, a separator 12 having discharge spaces 13 formed therein, and an insulator plate 14 having thereon transparent or semi-transparent electrodes 15. If there occurs light irradiation or optical cross-talk between adjacent luminescent elements of the discharge luminescent element array 1, it disadvantageously reduces the resistance of the corresponding photoconductive element at the switched off time.

As an example of the discharge luminescence element array in which optical cross-talk is reduced to as low a degree as possible there is known a type in which the opaque separator 12' is formed into comb-like configuration as shown in FIG. 2. This separator can be provided on the insulator plates 11 and 14 by, for example, a printing method. However, since it is necessary for the separator to be printed with a high accuracy of several tens of microns when the spacing between the luminescence elements is low, the provision of the separator by this method is practically difficult.

SUMMARY OF THE INVENTION

The present invention is intended to overcome the above disadvantage of the prior art arrangement.

An object of the present invention is to provide a discharge luminescent element array in which optical cross-talk between discharge luminescent elements is much reduced and which is simple in structure.

The feature of the present invention is the provision of a gas flow path for evacuating and providing gas from and to discharge spaces formed by a pair of parallel plates and a separator interposed between and sealed to the pair of plates.

DESCRIPTION OF THE PREFERRED EMBODIMENT

An embodiment of the discharge luminescent element array according to the present invention is illustrated in FIGS. 3a and 3b in plan and elevational cross-sectional views, respectively. The discharge luminescent element array comprises a pair of parallel insulator plates 11 and 14, a separator 12'' interposed between the pair of insulating plates 11 and 14, and electrodes 10 and 15. A gas flow path 17 of any shape, for example a zigzag gas flow path, is provided to the separator 12'' and/or the insulator plate 11 or 14. The plates 11 and 14 and the separator 12'' are sealed together by cement, for example a glass material, to define discharge spaces 13.

The glass material used for the cement 18 is commonly formed by overlaying a mixture liquid of glass powder, nitrocellulose and its solvent, for example carbitol acetate, on the plates 11 and 14 or separator 12'' by, for example, a printing method and by firing, at which time the carbon in the nitrocellulose is partially separated to generally turn the cement pale grey.

The degree of optical cross-talk between the luminescent elements due to the light transmission through the glass material 18 will next be calculated referring to FIG. 4 which is an enlarged view of a part of the luminescent element array between two adjacent luminescent elements shown in FIG. 3b. Denoting the intensity of incident light by P_0 , the intensity of transmitted light by P_t , and the distance between two adjacent luminescent elements by t_1 and putting the photo-penetrating power at $t = t_1$ as $T_1 (= (P_t)_{t=t_1}/P_0)$ and that at $t = t_2$ as $T_2 (= (P_t)_{t=t_2}/P_0)$, T_2 is given by $T_2 = (T_1)^{t_2/t_1}$

Since the photo-penetrating power of glass material at $t_1 =$ about 50 microns is commonly of the order of 40 to 70 percent, the optical cross-talk or light leakage between two luminescent elements, i.e., the photo-penetrating power T_2 , can be provided by putting the distance t between two luminescent elements approximately at t_2 . For example, for $T_1 = 70$ percent, $t_1 = 50 \mu$, and $t_2 = 2$ mm, T_2 is given by $T_2 \approx 10^{-6}$ from Equation (1). This is a very small value. Thus, the amount of light irradiation or light leakage to the adjacent luminescent element can markedly be reduced by employing a material of a suitable light attenuation as a cement.

If the separator 12'' is entirely sealed to the plates 11 and 14, the discharge spaces 13 are made airtight so that the gas in the discharge spaces cannot be evacuated nor can the discharge spaces be filled with any discharge gas. For this reason it is necessary to provide the discharge spaces 13 with the gas flow path 17. It is effective for the gas flow path to be formed into a narrow zigzag groove shape to give a light shielding effect.

As a practical example, for the transparent glass plates 11 and 14 each having a thickness of 0.3 mm, the separator 12'' of a glass filter having a high photoabsorptive power (Corning glass filter No. 7-56; Trade Mark), and the spacing between adjacent two luminescent elements of a 2.5 mm, the light leakage is about 10^{-4} . On the other hand, when the separator 12'' is not entirely sealed, but sealed only at its peripheral portion, the light leakage or optical cross-talk is about 5×10^{-3} . Thus, the present invention can reduce the optical cross-talk to about one-fiftieth or less.

The reason why the degree of the optical cross-talk in the above practical example is considerably higher than the calculated value is that light is transmitted through the glass plates 11 and 14 rather than through the cement 18. Consequently, by employing filter glass plates having a suitable photo-absorptive power as the insulator plates 11 and 14 the optical cross-talk could be reduced to the order of the calculated value.

Though in FIGS. 3a and 3b the gas flow path 17 between adjacent two discharge spaces 13 is a segmental line having only one break point, it can advantageously have a number of break points. However, if so high a light attenuation is not required, the gas flow path 17 can be made a straight line having no break point.

I claim:

1. In a discharge luminescence element array comprising a pair of parallel insulator plates, electrodes provided on the outer faces of said pair of insulator plates, and a separator interposed between said pair of insulator plates, said separator having a plurality of apertures formed therein defining the same plurality of discharge spaces with said pair of insulator plates, the improvement comprising a groove-like gas flow path provided at the interface between one of said pair of insulator plates and said separator for evacuating gas from and providing a discharge gas to said discharge spaces, said separator being sealed at its entire main faces to said pair of insulator plates.

2. A discharge luminescence element array according to claim 1, in which said gas flow path between adjacent discharge spaces is a zigzag segmental line.

3. A discharge luminescence element array according to claim 1, in which each of said insulator plates is a filter glass plate.

4. In a discharge luminescence element array comprising:

a pair of spaced apart insulator plates;
electrodes provided on the outer faces of said pair of insulator plates;
a separator interposed between the inner faces of said pair of insulator plates, said separator having a plurality of apertures formed therein defining a plurality of discharge spaces confined between said insulator plates, which discharge spaces terminate at said inner faces of said insulator plates; and
a gas flow path provided through said separator so as to provide a fluid connection between said discharge spaces;

the improvement comprising

means for sealing said separator at the respective interfaces thereof with said inner faces of said pair of insulator plates comprising a light absorbent ce-

ment.

5. The improvement according to claim 4, wherein said gas flow path comprises an aperture interconnecting respective individual ones of said discharge spaces with each other, the cross-section of said aperture being considerably less than the cross-section of said discharge spaces.

6. The improvement according to claim 4, wherein each of said insulator plates contains a filter glass material, said separator is made of a glass filter material having a high photoabsorptive power, and said cement is substantially opaque.

7. The improvement according to claim 6, wherein said gas flow path comprises an aperture interconnecting respective individual ones of said discharge spaces with each other, the cross-section of said aperture being considerably less than the cross section of said discharge spaces.

8. The improvement according to claim 6, wherein said gas flow path has a configuration which prevents direct linear optical communication between adjacent discharge spaces.

9. The improvement according to claim 8, in which said gas flow path between adjacent discharging spaces is a zigzag segmental line.

10. In a discharge luminescence element array comprising:

a pair of spaced apart insulator plates;
electrodes provided on the outer faces of said pair of insulator plates;
a separator interposed at and sealed between the inner faces of said pair of insulator plates, said separator having a plurality of apertures formed therein defining a plurality of discharge spaces confined between said insulator plates; and
a gas flow path provided through said separator so as to provide a fluid connection between said discharge spaces;
the improvement wherein said gas flow path between adjacent pairs of discharge spaces follows a path which prevents direct optical communication between the adjacent discharge spaces connected thereby.

11. The improvement according to claim 10, wherein the gas flow path between an adjacent pair of discharge spaces follows a zig-zag path.

12. The improvement according to claim 10, wherein said separator is sealed at the respective interfaces thereof with the inner faces of said pair of insulator plates by a light absorbent cement.
